Walter V. Reichard.

UNITED STATES PATENT OFFICE.

WALTER V. REICHARD, OF PAOLA, KANSAS.

THERMAL CIRCUIT-CLOSER.

1,398,153.

Specification of Letters Patent.

Patented Nov. 22, 1921.

Application filed March 3, 1921. Serial No. 450,816.

To all whom it may concern:

Be it known that I, WALTER V. REICHARD, a citizen of the United States, residing at Paola, in the county of Miami and State of Kansas, have invented certain new and useful Improvements in Thermal Circuit-Closers; and I do declare the following to be a full, clear, and exact description of the invention, such as will enable others skilled in the art to which it appertains to make and use the same.

This invention relates to an improved thermal circuit closer and one object of the invention is to provide an improved construction in the face and insulated terminal plate and to further provide an improved type of resilient circuit closing strip carried by one of the terminal plates and releasably held out of engagement with the second terminal plate by fusible metal.

Another object of the invention is to provide the terminal plate carrying the resilient contact strip with an improved cup-shaped device positioned beneath a cutout in the terminal plate and having an opening formed therein which will be normally closed by the fusible metal and through which the end portion of the resilient strip will pass when the fusible metal has been melted.

Another object of the invention is to so construct this cup that the free end portion of the resilient strip will be guided into the opening formed in this cup when the fusible metal has been melted.

Another object of the invention is to provide a thermal circuit closer which will be very efficient in operation and cheap to produce.

This invention is illustrated in the accompanying drawings, wherein:

Figure 1 is a view showing the improved thermal closer in top plan.

Fig. 2 is a side elevation of the thermal circuit closer shown in Fig. 1.

This improved device is used for sounding an alarm in case of fire and is provided with the spaced upper and lower relatively rigid terminal plates A and A' which will be secured upon a suitable insulating support such as the ledge L. The plate A is secured by the securing screws F and F' and the plate A' is secured by the securing screws H. From an inspection of Fig. 1, it will be seen that the signal bell I is connected with one of the securing screws H by means of a wire P' and that the battery

which is in circuit with the bell is connected with the securing screw F' by means of the wire P. Therefore, when the circuit is completed, the signal bell I will be sounded and an alarm given. The terminal plate A' is simply a flat strip of metal through which electric current will pass, this plate being positioned beneath the terminal plate A and as previously stated secured to the ledge L by the fastener screws H. The terminal plate A is also formed of sheet metal but this plate is bent adjacent one end to provide the upstanding neck D and a base E through which the securing screws F and F' pass. Adjacent the neck D, this upper plate A has been provided with a board having a threaded opening formed therein to receive the securing screw B' which engages the end of the resilient strip B to securely connect the strip B with the terminal plate A. This plate adjacent its free end is provided with a cutout K and a cup M is connected with the underface of the plate A to provide a guide which is positioned beneath and closes the opening K. An opening M' is formed in the center of the cup M and normally this opening M' will be covered by fusible metal N which will be dropped into the cup in a melted state and will harden in the cup and close the opening. This metal N may be formed of any suitable fusible metal but will preferably be a combination of lead, tin, cadmium and bismuth which melts at approximately 65° C., the equivalent of 149° F. The resilient strip B is bent adjacent its free end as shown at G thus providing a depending bill C which extends through the cutout K and rests upon the fusible metal N above the opening M'.

When this device is in use, the two terminal plates will be connected with the ledge L and the wires P and P', which lead from the bell and battery will be connected with the fasteners for these plates as shown. Under ordinary circumstances, the fusible metal will prevent the bill C from passing through the opening M' and the resilient strip will thus be prevented from having contact with the terminal plate A'. The circuit through the bell and battery will thus be broken and the signal will be prevented from being sounded. In case of fire, the fusible metal will melt and the bill will pass through the opening of the cup and down into contacting engagement with

the terminal plate A'. The circuit will thus be completed and the signal bell will ring. By providing the cup-shaped guide M, the bill will be guided into the opening 5 M' in case this bill should have been bent somewhat and thus the passage of the bill through the opening M' will be assured.

It will thus be seen that there has been provided a thermal circuit closer which will 10 be cheap to produce, easy to install and which will be very efficient in operation.

I claim:

1. In a thermal circuit closer, two strips of conducting material and a spring having 15 an L-shaped end, the strips being arranged one above the other; the upper strip having a hole in its outer end to allow the L-shaped end of the spring to pass through and touch the lower strip and the spring being fastened 20 to the upper strip, in combination with a piece of easily fusible metal attached to the upper side of the upper strip above the opening.

2. A thermal circuit closer comprising terminal plates positioned in spaced relation, 25 one of said plates having an opening formed therein, a cup connected with said last mentioned plate and inclosing the opening thereof, said cup having an opening formed 30 therein, fusible metal in the cup closing the opening thereof, and a strip of resilient metal connected with the terminal plate having the opening formed therein and having a free end portion provided with a bill extending through the opening of the plate 35 into said cup and having its end resting upon the fusible metal adjacent the opening formed in the cup.

3. A thermal circuit closer comprising terminal plates positioned one above the other, 40 the upper plate having a cutout above the

lower plate, a cup connected with the underface of the upper plate and inclosing the cutout thereof and provided with an opening closable by fusible metal placed in the cup, 45 and a strip of resilient metal connected with the upper plate and extending longitudinally thereof and having its free end portion provided with a bill extending downwardly through the cutout of the upper plate into 50 the cup and guided through the opening of the cup by the walls thereof when fusible metal closing the opening of the cup has been melted.

4. A thermal circuit closer comprising 55 upper and lower terminal plates, a cup carried by the upper plate and extending toward the lower plate and having an opening formed above the lower plate, and closable by fusible metal within the cup, and a strip 60 of resilient metal connected with the upper plate and having its free end portion provided with a bill extending into the cup and passing through the opening thereof when fusible metal closing the opening has been 65 melted.

5. In a thermal circuit closer spaced terminal strips positioned one above the other, the upper strip having an opening formed 70 therein above the lower strip, a resilient strip connected with the upper strip and having a bill to extend through the opening of the upper strip and engage the lower strip to close a circuit, and easily fusible metal upon the upper side of the upper strip closing 75 the opening formed therein and restraining the bill of the resilient strip from passing through the opening of the upper strip until melted.

In testimony whereof I have hereunto set 80 my hand.

WALTER V. REICHARD.
